APPARATUS FOR POURING MOLTEN METAL

Philip M. Hulme, Metuchen, N. J., assignor to
International Smelting and Refining Company,
a corporation of Montana

Application March 14, 1942, Serial No. 434,742

17 Claims. (Cl. 22—79)

This invention relates to apparatus for pouring molten metal, and has for its principal object to provide improved apparatus of this character. More particularly the invention contemplates the provision of an improved tilting ladle for receiving molten metal from a melting furnace and for pouring the metal into molds.

Ordinarily ladles for receiving metal from a furnace and for pouring it into a mold consist of open vessels into which the metal runs from a furnace tap hole. The ladle may then be carried to the molds into which the metal is to be cast. Other types of ladles consist of open tiltable vessels into which the molten metal runs substantially continuously from the furnace, and which may be intermittently tilted to pour the molten metal into molds as the latter are brought into position before the ladle. Such ladles are simple to make and to use, and are quite satisfactory in cases where contact between the molten metal and the atmosphere is not objectionable.

In United States Patent No. 2,265,284, granted December 9, 1941, on an application of Philip M. Hulme and Robert A. Ghelardi, assigned to the same assignee as this application, there is described a novel process for melting copper by means of radiant heat in a fuel-fired muffle type furnace. Copper melted by this process is substantially as pure as the solid copper charged into the melting furnace. If cathode copper is used as the solid charge, the molten copper produced in the furnace is very pure and substantially oxygen-free. If upon withdrawing this molten copper from the furnace it is allowed to come in contact with the air, it rapidly combines with atmospheric oxygen. Consequently, the copper must be withdrawn from the furnace and cast without coming in contact with the air if substantially oxygen-free cast shapes are to be produced.

In my copending application Serial No. 434,741, filed March 14, 1942, I have described and claimed a form of launder through which molten copper may be withdrawn from the melting furnace described in the aforementioned Hulme and Ghelardi patent, without permitting the copper to come in contact with the atmosphere. The present invention provides a form of pouring apparatus especially suitable for use in combination with a launder of the character described in my aforementioned copending application, whereby the molten copper withdrawn through the launder may be poured intermittently into molds without permitting contact of the metal with the air. The invention further provides a form of pouring apparatus such that the charge of

molten metal therein may be heated by means of radiant heat derived by the burning of fuel. This arrangement enables the molten metal to be kept in the molten state and at a suitable casting temperature by burning an inexpensive fuel, but without permitting the metal to come in contact with and be contaminated by the gaseous combustion products.

The new pouring apparatus comprises a tiltable ladle having a molten metal chamber in the lower portion thereof and a heating chamber in the upper portion. A thin, substantially gas-tight wall of heat-conducting refractory separates the metal chamber from the heating chamber. Means are provided for introducing hot combustion gases into the heating chamber, whereby the wall may be heated to an elevated temperature and may thereby supply sufficient radiant heat to the metal in the metal chamber to maintain it in the molten condition and at a suitable casting temperature, without allowing the metal to come in contact with any deleterious combustion gases.

Means are of course provided for introducing molten metal into the metal chamber in the ladle. Advantageously a refractory conduit extending from the upper exterior of the ladle through the heating chamber and the wall, and opening into the metal chamber, is provided for this purpose. Molten metal then may be poured from above the ladle through the conduit directly into the metal chamber without coming in contact with deleterious combustion gases in the heating chamber.

The ladle advantageously is substantially cylindrical and is tiltable about its axis. The substantially cylindrical upper exterior surface mates with a corresponding curved surface of the launder or other structure through which molten metal is delivered to the ladle. By virtue of these mating curved surfaces, the ladle may be tipped without creating any substantial aperture between the ladle and the launder.

The conduit through which molten metal is fed from above the ladle into the metal chamber opens to the exterior of the ladle immediately below the discharge from the launder, so as to receive metal from the launder. The mouth of the conduit adjacent the launder preferably is sufficiently wide so that metal may run continuously from the launder into the conduit even during normal tilting of the ladle.

The ladle of course is provided with a discharge spout through which molten metal may be poured into a mold when the ladle is tilted.

The new pouring apparatus will be better understood from the following description of the preferred embodiment shown in the accompanying drawings, in which

Fig. 1 is a vertical section through pouring apparatus constructed according to the invention and through the end portion of a launder for delivering molten metal to the ladle;

Fig. 2 is a front elevation of the ladle shown in Fig. 1; and

Fig. 3 is a plan looking down on the ladle shown in Figs. 1 and 2.

The ladle shown in the drawings comprises an outer steel shell 10 which is generally cylindrical in cross section. Trunnions 11 are secured substantially axially to the shell 10 at the ends of the ladle. The trunnions 11 are carried in journals 12 which in turn are mounted on a ladle car 13. As shown in the drawings, the ladle car 13 is supported by wheels 14 and 15 riding on channel-beam tracks 16. The wheels 14 riding on the top flange of the tracks 16, carry the weight of the car 13 and of the ladle. The wheels 15, engaging with the undersurface of the track top flange, serve to prevent the car 13 from tipping. By thus supporting the ladle on a car, it may be moved axially should this be desired for convenience in making any necessary repairs. It is understood, however, that it is not necessary for the ladle to be mounted on a movable car in the manner above described.

The steel shell 10 of the ladle is lined with refractory. An outer layer of insulating refractory 17 and an inner layer of refractory silica brick 18 are shown in the drawings. Any refractory or combination of refractories suitable for withstanding attack by the hot molten metal carried in the ladle may be employed.

The interior of the refractory-lined ladle is divided into a lower metal chamber 20 and an upper combustion chamber 21 by means of a thin refractory wall 22. An oil burner or other fuel burner 23 extends through the refractory wall at one end of the combustion chamber 21, for the purpose of introducing and burning fuel in the combustion chamber. The hot combustion gases thereby produced come in contact with the thin wall 22 forming the floor of the combustion chamber, and pass the length of the combustion chamber to an offtake flue 24. From the flue 24 the gases pass to a chimney flue 25. A hood 26 at the base of the chimney flue 25 serves to direct the combustion gases from the offtake flue 24 into the chimney flue 25, without preventing normal tilting of the ladle on its trunnions 11. If desired, the gases may be delivered by the flue 25 to a waste heat boiler or other heat-recuperating means before they are allowed to escape to the atmosphere.

The thin refractory wall 22 forms a substantially gas-tight barrier between the combustion chamber 21 and the metal chamber 20, so that there is no opportunity for deleterious components of the combustion gases to come in contact with molten metal in the metal chamber. The wall 22, however, should be thin and made of a refractory having good heat-conducting properties, such, for example, as silicon carbide. The hot combustion gases heat the wall 22 sufficiently so that it may supply radiant heat to the metal in the metal chamber and may thereby maintain it at an elevated temperature above the melting point of the metal and high enough for satisfactory casting.

The above-described arrangement for supply-

ing radiant heat to the metal in the ladle permits providing this heat by the inexpensive process of burning a fuel, but without permitting the molten copper or other metal to be contaminated by the deleterious products of the fuel combustion. Of course, some of the heat is transferred to the molten metal by conduction through the refractory lining 18, rather than by radiation from the wall 18, but this mode of heat transfer obviously does not produce any detrimental effect.

A conduit in the form of a refractory pipe 27 extends from the upper exterior of the ladle through the refractory layers 17 and 18, the combustion chamber 21 and the wall 22, and opens into the metal chamber 20. This refractory pipe provides means for pouring molten metal from above the ladle directly into the metal chamber, without permitting the metal to come in contact with contaminating gases in the combustion chamber. Silicon carbide is a satisfactory material from which to form the pipe 27.

As illustrated in Fig. 1, the ladle advantageously is used in combination with a launder of the character described and claimed in my aforementioned copending application Serial No. 434-741, filed March 14, 1942. This launder comprises a fully enclosed trough 28 through which molten metal flows to its discharge end 29. A housing 30 at the end of the launder structure provides an enclosure about the discharge end 29 of the launder trough. The housing 30 may be fitted with a window 31 to permit observation of the molten metal as it flows from the discharge end of the launder into the ladle. The upper cylindrical surface 32 of the ladle shell mates with a corresponding cylindrically curved surface at the underside of the launder structure and housing 30. The axis of the cylindrically curved portion 32 of the ladle, and of the mating curved surface of the launder structure, coincides with the axis of the trunnions 11. The ladle therefore may be tilted on its trunnions without creating any substantial aperture between the launder and the ladle.

The ladle is of course positioned so that the mouth of the pipe 27 at the exterior of the ladle lies directly beneath the discharge end 29 of the ladle trough. Hence molten metal flowing from the launder falls through the pipe 27 into the metal chamber 20. Inasmuch as there is no substantial aperture between the launder and the ladle, the metal from the launder passes into the ladle without coming into contact with the atmosphere.

As described in my aforementioned copending application Serial No. 434,741, means may be provided for introducing a protective gas atmosphere into the enclosed trough 28, preferably under a slight positive pressure. Any protective gas introduced into the enclosed trough 28 will of course pass freely into the pipe 27 and the metal chamber 20 of the ladle, thereby providing additional protection against contact of the molten copper or other metal with any deleterious gas. Moreover, such protective gas introduced under slight positive pressure into the enclosed trough 28 of the launder will slowly flow out through any slight aperture or crack that may unavoidably exist at the juncture between the ladle and the launder, and so will provide a gas seal effectively preventing the entrance of air into the interior of the launder trough 28 or the pipe 27.

The mouth of the pipe 27 advantageously is

sufficiently wide so that molten metal may flow into it continuously from the discharge end of the launder, even during normal tilting of the ladle. For this reason it is generally advantageous to make the pipe 27 oval in cross section, as shown in Fig. 3, and to mount the pipe so that its greatest internal diameter is at a right angle to the axis about which the ladle tilts. The maximum diameter of the pipe 27 necessary to enable it to receive a continuous flow of metal of course depends on the angle through which the ladle is designed to be tilted during casting operations. Ordinarily this angle is quite small, being of the order of 5 to 15 degrees.

An opening 33 is formed through the refractory lining of the ladle to permit molten metal to flow from the metal chamber to the pouring spout. The spout may consist simply of an opening 34 formed in the ladle shell. The opening 33 formed in the refractory advantageously slopes downwardly from the spout 34 so that it communicates with the interior of the metal chamber wholly below the surface of the molten metal in the ladle. In this manner any opportunity for air or other deleterious gas to gain access to the interior of the metal chamber through the spout 34 and the opening 33 is minimized. If desired, a refractory door 35 may be provided to close the opening 33 at all times except when actually pouring metal through the ladle spout. This door, which may be opened and closed manually, further insures against entrance of contaminating gases into the metal chamber through the opening 33.

In order to cast substantially oxygen-free metal from the ladle metal chamber into molds 36, a gas hood 37 may be provided. As shown in the drawings, the outer surface 38 of the ladle shell in the vicinity of the spout 34 is curved cylindrically, with the axis of curvature coinciding with the axis of the trunnions 11 on which the ladle is tilted. The gas hood 37 is mounted on stationary brackets and so does not tilt with the ladle, but where it joins with the ladle, it is curved cylindrically to conform with the curvature of the surface 38. Hence tilting of the ladle about its axis does not create any substantial aperture between the ladle and the hood.

A pipe 40 may be provided for introducing a protective gas into the interior of the pouring hood 37. An ample supply of protective gas should be delivered through the pipe 40, so that when the mold 36 is brought into position beneath the hood 37, the outflow of gas through the aperture between the hood and the mold is sufficient to prevent the inflow of contaminating gases from the atmosphere. The mold 36 may itself be filled with gas just before being brought into position under the hood 37. A funnel 41 may be built into the protective hood so as properly to direct the flow of metal from the ladle spout 34 into the mold 36.

In some cases, as, for example, in casting phosphor-copper billets, it is not necessary to employ the hood 37 or equivalent protective device. The short time of contact of the molten phosphor copper with the air in flowing from the spout 34 into the mold 36 is not of sufficient duration to affect the alloy detrimentally. However, in casting oxygen-free high-conductivity copper, the hood 37 or equivalent protective device is generally necessary.

A hopper 42 may be provided for introducing alloying ingredients, such as phosphor-copper or silicon copper master alloy, into the molten metal

10 in the ladle. The bottom of the hopper 42 is closed by a manually operated valve or gate 43, below which is a conduit 44 extending through the housing 31 at the end of the launder to a point directly above the pipe 27. When the valve or gate 43 is operated by turning the wheel 45, a slug of the alloying ingredient may be dropped through the pipe 44 and the refractory pipe 27 into the molten metal in the ladle. Advantageously the slugs of alloying ingredient are of such size that the wheel 45 may be manipulated to drop one into the metal in the ladle either just before or just after each time the ladle is tilted to fill a mold.

15 I claim:

1. Apparatus for pouring molten metal comprising a tiltable ladle having a molten metal chamber in the lower portion thereof and a combustion chamber in the upper portion thereof, a thin, substantially gas-tight wall of heat-conducting refractory material separating said metal chamber from said combustion chamber, means for introducing hot combustion gases into the combustion chamber in contact with said wall, whereby the wall may be heated to an elevated temperature and may thereby supply sufficient radiant heat to the metal in the molten metal chamber to maintain said metal in the molten condition, means for introducing a continuous stream of molten metal into the metal chamber even during tilting of the ladle, and means for discharging molten metal therefrom upon tilting of the ladle.

2. Apparatus for pouring molten metal comprising a tiltable ladle having a molten metal chamber in the lower portion thereof and a combustion chamber in the upper portion thereof, a thin, substantially gas-tight wall of heat-conducting refractory material separating said metal chamber from said combustion chamber, means for introducing hot combustion gases into the combustion chamber in contact with said wall, whereby the wall may be heated to an elevated temperature and may thereby supply sufficient radiant heat to the metal in the molten metal chamber to maintain said metal in the molten condition, a refractory pipe open at both ends extending through the combustion chamber and communicating with the interior of the metal chamber for pouring a continuous stream of molten metal from above into the metal chamber even during tilting of the ladle, and a spout through which molten metal may be discharged from the metal chamber upon tilting of the ladle.

3. Apparatus for pouring molten metal comprising a substantially cylindrical ladle tiltable through an arc about its axis, a molten metal chamber in the lower portion of the interior of said ladle and a combustion chamber in the upper portion of the interior thereof, a thin, substantially gas-tight wall of heat-conducting refractory material separating said metal chamber from said combustion chamber, means for introducing hot combustion gases into the combustion chamber in contact with said wall, whereby the wall may be heated to an elevated temperature and may thereby supply sufficient radiant heat to the metal in the metal chamber to maintain it in the molten condition, means for introducing a continuous stream of molten metal into the metal chamber even during tilting of the ladle, and means for discharging molten metal therefrom upon tilting of the ladle.

4. A muffle ladle of the character described

comprising a tiltable vessel having a molten metal chamber in the lower portion thereof and a heating chamber in the upper portion thereof, a thin, substantially gas-tight heat-conducting refractory wall separating said metal chamber from said heating chamber but capable of receiving heat from within the heating chamber and of transmitting radiant heat to metal in the metal chamber, means for introducing hot combustion gases into said heating chamber, means for introducing a continuous stream of molten metal into said metal chamber even during tilting of the ladle, and means for discharging metal from the metal chamber upon tilting of the ladle vessel.

5. A muffle ladle of the character described comprising a substantially cylindrical refractory-lined vessel, means for tilting said vessel through an arc about its axis, a molten metal chamber in the lower portion of said vessel and a combustion chamber in the upper portion thereof, a thin, substantially gas-tight heat-conducting wall separating said metal chamber from said combustion chamber but capable of receiving heat from within the combustion chamber and of transmitting radiant heat to metal in the metal chamber, means for burning fuel in the combustion chamber, means for introducing a continuous stream of molten metal into the metal chamber even during tilting of the ladle, and means for discharging molten metal therefrom upon tilting of the ladle vessel.

6. A muffle ladle of the character described comprising a tiltable vessel having a molten metal chamber in the lower portion thereof and a heating chamber in the upper portion thereof, a thin, substantially gas-tight heat-conducting refractory wall separating said metal chamber from said heating chamber but capable of receiving heat from within the heating chamber and of transmitting radiant heat to metal in the metal chamber, means for introducing hot combustion gases into said heating chamber, an enclosed conduit open at both ends extending through the heating chamber and opening into the metal chamber through which a continuous stream of molten metal may be introduced from above the ladle into the metal chamber even during tilting of the ladle, and means for discharging molten metal from the metal chamber upon tilting of the ladle vessel.

7. A muffle ladle of the character described comprising a substantially cylindrical refractory-lined vessel, means for tilting said vessel through an arc about its axis, a molten metal chamber in the lower portion of said vessel and a combustion chamber in the upper portion thereof, a thin, substantially gas-tight heat-conducting wall separating said metal chamber from said combustion chamber but capable of receiving heat from within the combustion chamber and of transmitting radiant heat to metal in the metal chamber, means for burning fuel in the combustion chamber, a refractory pipe open at both ends extending from the outer surface of the ladle vessel through the combustion chamber and opening into the metal chamber, the open end of said pipe adjacent the outer surface of the ladle being at least substantially as wide in the direction in which the ladle tilts as the distance through which the ladle normally tilts, whereby a continuous stream of molten metal may be poured from above the ladle vessel directly into the metal chamber even during tilting of the ladle, and a spout through which molten metal may be poured

from the metal chamber upon tilting of the ladle vessel.

8. In a tiltable muffle ladle having a molten metal chamber in the lower interior thereof and a heating chamber in the upper interior thereof with a wall therebetween, a conduit open at both ends extending from the upper exterior of said ladle through said combustion chamber and said wall and opening into said metal chamber, whereby a continuous stream of molten metal may be poured from above the ladle directly into the metal chamber even during tilting of the ladle.

10 9. A tiltable muffle ladle having a molten metal chamber in the lower interior thereof and a heating chamber in the upper interior thereof with a wall therebetween, and a conduit extending from the upper exterior of said ladle through said combustion chamber and said wall and opening into the interior of the metal chamber, the exterior of said ladle being curved uniformly adjacent said conduit so as to mate with a correspondingly curved end structure of a launder, and the extent and shape of said ladle curvature being such as to permit tilting of the ladle relatively to the launder end structure without creating any substantial aperture therebetween.

15 10. A tiltable muffle ladle having a molten metal chamber in the lower interior thereof and a heating chamber in the upper interior thereof with a wall therebetween, and a conduit extending from the upper exterior of said ladle through said combustion chamber and said wall and opening into the interior of the metal chamber, the exterior of said ladle being curved uniformly adjacent said conduit so as to mate with a correspondingly curved end structure of a launder, the extent and shape of said ladle curvature being such as to permit tilting of the ladle relatively to the launder end structure without creating any substantial aperture therebetween, and the mouth of said conduit adjacent the exterior of the ladle being sufficiently large to receive a continuous flow of metal from the launder during normal tilting of the ladle.

15 11. The combination with a launder for molten metal having a curved under-surface adjacent its discharge end, of a tiltable ladle having a corresponding curved upper-surface substantially mating with said launder under-surface, said ladle having a metal-receiving passage opening to the curved upper exterior thereof, the mouth of said passage at the exterior of the ladle being sufficiently large to receive a continuous flow of metal from the launder during normal tilting of the ladle.

55 12. The combination with a launder for molten metal having a curved under-surface adjacent its discharge end, of a tiltable ladle having a corresponding curved upper-surface substantially mating with said launder under-surface, said ladle having a metal-receiving passage opening to the curved upper exterior thereof, and the curved juncture of said ladle with said launder being such as to permit tilting of the ladle relatively to the launder without thereby creating any substantial aperture therebetween.

60 13. The combination with an enclosed launder for molten metal having a curved under-surface adjacent its discharge end, of a tiltable muffle ladle having a curved upper-surface substantially mating with said launder undersurface, said ladle having a molten metal chamber in the lower interior thereof and a heating chamber in the upper interior thereof with a substantially gas-tight wall therebetween, and a conduit

extending from the curved upper-surface of the ladle through said heating chamber and wall and opening into the molten metal chamber, the mouth of said conduit at the upper-surface of the ladle being substantially directly beneath the discharge end of the launder and being sufficiently wide to receive a continuous stream of molten metal during normal tilting of the ladle, and the curvatures of the launder under-surface and the mating ladle upper-surface being such as to permit normal tilting of the ladle without creating any substantial aperture therebetween, whereby molten metal may be poured continuously from the launder through the conduit into the ladle metal chamber without coming in contact with deleterious gases either in the atmosphere or in the heating chamber.

14. An assembly of launder and pouring ladle for the casting of molten metal comprising an enclosed launder capable of conveying a stream of molten metal to its discharge end, a ladle arranged adjacent the metal discharge point of said launder in tilttable relation therewith and adapted to receive continuously during normal tilting movement thereof the stream of molten metal discharging from the launder, the arrangement of launder and ladle being such as to permit tilting of the ladle relatively to the launder without thereby permitting any substantial exposure of the stream of molten metal to the atmosphere.

15. An assembly of launder and pouring ladle for the casting of molten metal comprising an enclosed launder, a ladle arranged adjacent the metal discharge point of said launder in tilttable relation therewith, said ladle having a molten metal chamber in the lower portion thereof and a heating chamber in the upper portion thereof with a substantially gas-tight wall therebetween, and a conduit in said ladle extending from adjacent the discharge end of the launder through said heating chamber and wall and opening into

the molten metal chamber, the arrangement of said launder, ladle, and conduit being such as to permit continuous flow of metal from the launder discharge into and through the conduit during tilting of the ladle, and further being such as to permit tilting of the ladle without thereby permitting any substantial exposure of the stream of molten metal to deleterious gases in the atmosphere or in the ladle heating chamber.

16. A tilttable ladle having a molten metal chamber therein, and a spout through which molten metal may be poured from said chamber upon tilting of the ladle, the exterior surface of said ladle in the vicinity of the spout being curved uniformly adjacent said spout, in combination with a hood enclosing said spout, and means for introducing a protective gas into the interior of said hood, the hood at its juncture with the ladle being curved to conform with the aforesaid curvature of the ladle exterior surface, whereby the ladle may be tilted relatively to the hood without creating any substantial aperture between the ladle and hood.
17. A tilttable ladle having a molten metal chamber therein, and a spout through which molten metal may be poured from said chamber upon tilting of the ladle, the exterior surface of said ladle in the vicinity of the spout being curved substantially cylindrically through an arc having its axis substantially coincident with the axis about which the ladle tilts, in combination with a stationary hood enclosing said spout and the stream of metal issuing therefrom when the ladle is tilted to pouring position, and means for introducing a protective gas into the interior of said hood, the hood at its juncture with the ladle being curved to conform with the aforesaid curvature of the ladle exterior surface, whereby the ladle may be tilted relatively to the hood without creating any substantial aperture between the ladle and hood.

PHILIP M. HULME.

CERTIFICATE OF CORRECTION.

Patent No. 2,329,049.

September 7, 1943.

PHILIP M. HULME.

It is hereby certified that error appears in the printed specification of the above numbered patent requiring correction as follows: page 3, second column, line 50, claim 2, for the word "steam" read --stream--; and that the said Letters Patent should be read with this correction therein that the same may conform to the record of the case in the Patent Office.

Signed and sealed this 26th day of October, A. D. 1943.
